US00D815938S

(12) **United States Design Patent** (10) **Patent No.:** **US D815,938 S**
MacDonald et al. (45) **Date of Patent:** **** Apr. 24, 2018**

(54) **CONNECTOR**

(71) Applicants: **Robert A. MacDonald**, Plymouth, MN (US); **Robert John Lundell**, Stillwater, MN (US)

(72) Inventors: **Robert A. MacDonald**, Plymouth, MN (US); **Robert John Lundell**, Stillwater, MN (US)

(73) Assignee: **KEYSTONE RETAINING WALL SYSTEMS LLC**, West Chester, OH (US)

(**) Term: **15 Years**

(21) Appl. No.: **29/571,777**

(22) Filed: **Jul. 21, 2016**

(51) **LOC (11) Cl.** **08-08**
 (52) **U.S. Cl.**

USPC **D8/382**
